UNITED STATES PATENT OFFICE

GEORGE P. WIGGINTON, OF KALAMAZOO, MICHIGAN, ASSIGNOR, BY MESNE ASSIGNMENTS, TO REMINGTON RAND INC., OF NEW YORK, N. Y., A CORPORATION OF DELAWARE

TEMPORARY BINDER

Application filed April 29, 1927. Serial No. 187,498.

The main object of this invention is to provide an improved temporary binder which is well adapted for holding loose sheets, circul-lars and the like, may be formed of very light material and, if desired, flexible material and at the same time is durable and the parts re-tained in proper relation.

Objects pertaining to details and economies of my invention will appear from the de-scription to follow. The invention is pointed out in the claims.

A structure embodying the features of my invention is clearly illustrated in the accom-panying drawing, in which:

15 Fig. 1 is a perspective view of my improved binder.

Fig. 2 is a vertical section on line 2—2 of Figs. 1 and 3.

Fig. 3 is a detail section on line 3—3 of 20 Figs. 1 and 2.

Fig. 4 is a detail inside view with the sheets removed showing the mounting of the locking slides.

Fig. 5 is a perspective view of one of the 25 sheet binding posts.

Fig. 6 is a perspective view of the transfer bar.

In the embodiment illustrated in the ac- 30 companying drawing, the covers 1, 1, the binding members 2 and 3 and the back 4 are formed of a single sheet of flexible material folded upon itself to form the binding mem-bers. The bottom binding member 2 is pro- 35 vided with posts 5, these posts being pro-vided with flange-like base members 6 at their lower ends and with clamping collars 7 which secure the posts to the binding member 2. The outer ends of the posts are reduced pro- 40 viding shoulders 8, annular grooves 9 being formed in these reduced portions providing heads 10. The top binding member 3 has holes 11 therein adapted to receive the ends of the posts.

Locking slides 12 formed of thin sheet 45 metal are mounted on this top binding mem-ber and have longitudinal slots 13 therein with central enlargements 14 adapted to be brought into alinement with the holes 13 to receive the ends of the post and permit the 50 slides being shifted longitudinally to engage

the edges of the slots in the grooves 9 of the posts or below the heads 10, thereby locking the binding members together.

The slides are engageably supported by means of the headed studs 15 engaging the slots 13, one of the studs being positioned to constitute a stop, see the dotted position of the slides, facilitating the positioning of the slides to receive or permit disengagement of the posts. The studs 15 and the posts con- 69. stitute means for retaining the parts of the sheet forming the binding members in their folded position.

I provide a transfer bar 16 with pins 17 adapted to engage holes 18 in the body of the 65 sheet 19. These transfer bars have holes 20 adapted to receive the reduced ends of the post 5 resting on the shoulders thereof, the transfer bar being arranged on the inner side of the top binding member 3. The pins 17 70. coact with the posts 5 in supporting the pin in the binder, the bar 16 being formed of metal and constituting a reinforcing member for the binder. This is a desirable feature when the covers and binding members are made up 75. of a sheet of flexible material as in the struc-ture illustrated.

With the parts thus arranged I have found it entirely practical to form the cover, bind-ing members and back as illustrated of a 80. sheet of heavy paper, such a binder being adapted for many uses.

My improved binders are very economical to produce, are light and compact in struc-ture and at the same time are durable.

Having thus described my invention what I claim as new and desire to secure by Let-ters Patent is:

1. A temporary binder comprising a pair 90 of cover members and a back formed of a single piece of flexible material folded upon itself to form a pair of binding members, a plurality of posts carried by one of said binding members and having a connection thereto for maintaining said member in fold-ed relation and adapted to project through openings provided in a group of sheets and in the other of said binding members, said posts having reduced ends forming shoul-ders and with annular grooves adjacent to the 95 100

extremities thereof, a transfer bar detachably associated with the other of said binding members and having openings therein adapted to receive the reduced ends of said posts and to abut the shoulders formed thereon, and locking members movably mounted on said last-mentioned binding member and having a connection thereto for maintaining said member in folded relation, said locking members having slots formed therein having enlarged portions through which the reduced ends of said posts are adapted to project, and reduced portions the edges of which are adapted to enter the annular grooves provided on said posts when the locking members are moved into locking position relative to said posts.

2. A temporary binder comprising a pair of cover members and a back formed of a single piece of flexible material folded upon itself to form a pair of binding members, a plurality of posts carried by one of said binding members and having a connection thereto for maintaining said member in folded relation and adapted to project through openings provided in a group of sheets and in the other of said binding members, said posts having reduced ends forming shoulders and with annular grooves adjacent to the extremities thereof, a transfer bar detachably associated with the other of said binding members and having openings therein adapted to receive the reduced ends of said posts and to abut the shoulders formed thereon, locking members slidably mounted on said last-mentioned binding member and having a connection thereto for maintaining said member in folded relation, said locking members having slots formed therein having enlarged portions through which the reduced ends of said posts are adapted to project, and reduced portions the edges of which are adapted to enter the annular grooves provided on said posts when the locking members are slid into locking position relative to said posts, and a plurality of posts carried by said transfer bar to project through openings provided in said group of sheets for maintaining sheets in position with the first-mentioned openings in registry when removed from the binder.

3. A temporary binder comprising a pair of cover members and a back formed of a single piece of flexible sheet material folded upon itself between the back and the covers to provide a pair of inwardly directed binding members, leaf posts permanently attached at one end to one binding member and securing the fold portions thereof together, the opposite ends of said leaf posts being formed with grooves, and extended through openings in the other binding member, locking slides slidable on the outer side of said other binding member having portions to engage in the grooves in said leaf posts in one posi-

tion and disengaged from said posts in another position, studs extending through said locking slides and the fold portions of said other binding member provided with heads at opposite ends retaining said fold portions together and slidably retaining said locking slides thereon for slidable movement into engaged and disengaged relation with said leaf posts, and a substantially rigid metal transfer bar formed with openings to receive said leaf posts, detachably mounted against the inner surface of said other binding member and having leaf-supporting posts thereon, said transfer bar cooperating with said leaf posts in the engaged relation of said locking slides with said leaf posts to detachably support a sheet body between the fold portions of said flexible sheet forming said binding members, said transfer bar cooperating to retain said binder parts and sheet body in substantially rigid relation at the binding edge in assembled relation and forming the only metal form-retaining bar in said binder.

In witness whereof I have hereunto set my hand.

GEORGE P. WIGGINTON.
